[57] CLAIM

The ornamental design for an open side top for jeeps, substantially as shown and described.

DESCRIPTION

FIG. 1 is a perspective view of an open side top for jeeps showing my new design, it being understood that the broken lines are for illustrative purposes only; FIG. 2 is a front elevational view thereof with the rear tie down straps being shown cut off for convenience of illustration;

FIG. 3 is a rear elevational view of FIG. 2;
FIG. 4 is a side elevational view of FIG. 2; and
FIG. 5 is a top plan view of FIG. 2.
